APPARATUS FOR SCREENING ORE

Charles A. Gallagher and Carl M. Allen, California, Pa., assignors to General Chemical Company, New York, N. Y., a corporation of New York

Application May 24, 1933, Serial No. 672,556

6 Claims. (Cl. 209—257)

This invention is directed to apparatus for roasting metallic sulfides, and more particularly for roasting finely divided sulfide ores, to desulfurize the same and to produce sulfur dioxide 5 for use in the manufacture of sulfuric acid, or for any other purpose desired.

Generally speaking, to a large extent present practice in roasting sulfide fines includes the use of mechanically operated multiple hearth 10 constructions, such, for example, as the well known MacDougal, Herreshoff and Wedge burners, and while such burners provide effective roasting, the complicated construction and operation thereof involve considerable initial and 15 maintenance expense.

As distinguished from "bed" roasting carried out in such burners, it has been previously suggested to roast fines while in gaseous suspension, in operations in which the fines are either injected into a roasting chamber in suspension in 20 the oxidizing gas, or are showered downwardly into a roasting chamber wherein the fines encounter cross or counter-currents of oxidizing and/or suspending gas.

Suspension roasting is best applicable when 25 the fines ores are in a relatively finely divided state, and this method presents the notable advantage over the mechanical multiple hearth operation of considerably lowering the cost of 30 production, by reason of the elimination of complicated and moving parts, expensive rabbling and other apparatus inherent in the construction and operation of mechanical burners. In the practice of suspension roasting, however, and 35 particularly as applied to roasting metallic sulfide fines, difficulties are encountered which must be overcome before theoretical advantages of this type of roasting are made practicable available.

One of such difficulties involves introduction 40 of fines into the combustion chamber, and the formation of a uniform dispersion of ore particles therein. This phase of the process usually requires, for efficient conduct thereof, a relatively dry ore, free from lumps and extraneous foreign 45 material. Damp or wet ore tends to clog feed pipes and injector mechanisms thus interfering with operations in this respect. The presence of lumps in the fines, after introduction into the 50 combustion chamber, is detrimental to the formation of a satisfactory ore dispersion in the roasting atmosphere. Furthermore, large lumps once in the roasting chamber are relatively incompletely desulfurized, appreciable quantities 55 of sulfide sulfur being retained therein, thus in-

creasing the sulfur content of the cinder, and lowering the efficiency of roasting.

To avoid such difficulties, it is desirable to feed into the furnace, dry, or dry and preheated ore free from lumps. This requires screening, and 5 screening should preferably be effected after drying, as when damp ore is screened, the damp material tends to clog the screens. Moreover, if the fines are screened prior to drying, lumps which may form during drying are injected, as 10 such, into the combustion chamber. Hence, for efficient operation of processes for roasting metallic sulfides in gaseous suspension, it is preferable to dry or dry and preheat the fines, and subsequently screen the same before charging 15 into the furnace.

Prior screening devices, while effective in a general way, have been more or less objectionable because of attention required to keep such devices in operation, to prevent clogging with lumps 20 and foreign material and to prevent overflow of fine material therefrom. It has also been proposed to dry fines ores prior to injection into the combustion chamber by causing the ore to pass in heat exchange relation over the top and 25 sides of the combustion chamber thus utilizing radiated and conducted heat to dry the ore.

It is one of the principal objects of the invention to provide satisfactory mechanism for screening ore before feeding the same into the furnace 30 injectors. Another object is to provide a screening device which is automatic in operation and which does not require attention of an operator. The invention contemplates apparatus for preliminary drying or drying and preheating of the 35 fines, and for screening such fines, prior to injection into the roasting chamber.

With respect to the improved screening mechanism some of the important features thereof 40 comprise provision for regulation of the amount of fines fed to the screen surface to that withdrawn from the subjacent screen hopper conducting the screened fines into the injector mechanism; continuous withdrawal from the screen of oversized and foreign material; an auxiliary 45 overflow screen and hopper, positioned beyond the main screen surface and associated hopper, which overflow screen and hopper act to prevent discharge from the screening device of undersized material, thus preventing loss of the latter; and an arrangement by which material is 50 discharged from the overflow hopper into the fines injector faster than from the main hopper, so that the overflow hopper cannot become filled and cease to function in the intended capacity. 55

The objects and advantages of the invention may be more clearly understood from a consideration of the following description taken in connection with the accompanying drawings in which—

Fig. 1 is a vertical section of a burner in connection with which the improvements of the invention may be advantageously employed;

Fig. 2 is an enlarged, vertical section of a fines ore injector mechanism;

Fig. 3 is a vertical section of another type of burner illustrating another adaptation of the screening device of the invention;

Fig. 4 is an enlarged, vertical section of the improved screening device, showing a portion of a burner such as illustrated in Fig. 3;

Fig. 5 is a plan view of the hopper of the screening device;

Fig. 6 is an elevation of the hopper taken substantially on the line 6—6 of Fig. 4;

Fig. 7 is a development, on a reduced scale, of an ore drying and heating jacket surrounding the walls of the burner of Fig. 1, and

Figs. 8 and 9 are sections of a hopper screen agitator.

Referring particularly to Fig. 1 of the drawings, numeral 10 designates generally a shaft burner comprising a shell 11 constructed of suitable refractory material, such as firebrick, and defining a roasting or combustion chamber 12 of cylindrical cross-section. Surrounding the shell 11 is a steel casing 13, acting as a protective reinforcement for the furnace. The upper end of the combustion chamber is closed off by a crown 15, the top side of which forms a drying and preheating hearth 17. The cylindrical shell 11 and casing 13 project upwardly beyond the crown, and carry a framework 18 which in turn supports ore feeding and rabbelling mechanism for hearth 17.

The surface of hearth 17 is slightly cone-shaped and slopes downwardly toward the shell of the burner. Lying above the hearth are rabbble arms 19, having downwardly projecting plows 20 pitched to work sulfide fines gradually toward the circumference of the drying hearth. Arms 19 are rotated by a motor 22 through shaft 23, supported in bearings so as to maintain the lower ends of the plows 20 properly spaced with respect to the surface of the drying hearth 17. An ore bin 24, mounted on framework 18, discharges ore onto a platform 25 from which fines are intermittently dropped onto approximately the center of hearth 17 by a sweep 27 rotating with shaft 23.

Surrounding the major portion of casing 13 are a plurality of louvers 30 which with casing 13 form an ore drying and preheating jacket designated generally by reference numeral 32, enveloping a substantial portion of the vertical walls 60 of the burner. Cut in shell 11, near the upper end, are downwardly sloping ore supply passages 34 through which ore is passed from the drying hearth 17 into the topmost louver 35 constituting the upper edge of jacket 32. The drawings shows, in section, two passages 34. Preferably, several such conduits may pass through the top of shell 11 at spaced points about the circumference of the burner so that, on rotation of the rabbble arms 19, fines are gradually fed through the openings 34 into the top of the drying jacket.

In the embodiment of the apparatus shown in Fig. 1 the jacket 32 is provided at the bottom with three outlets, indicated at 38, through which fines are fed into the subjacent screener, desig-

nated by reference numeral 40. As shown in section at the left of Fig. 1 immediately above screener 40, and also in elevation in Fig. 7, sloping side 42 of lowermost louver 43 is of greater length than the sides of other louvers so as to provide small hoppers, terminating in discharge openings 38. The bottom of jacket 32 is formed by sloping edges 45 which intersect lower louvers 43 several of the intermediate louvers 30, and are attached to steel casing 13. A development 10 of the louvers is shown in Fig. 7. Edges 45 of the jacket are sloped at an angle greater than the angle of repose of the sulfide fines, so that the latter run freely toward outlets 38 through which the material is fed into the screener 40. 15 The louvers are supported by ledge-like projections 48 of verticals 49 which in turn may be suspended from framework 18. The louvers rest loosely on the projections, this arrangement permitting repair or replacement. 20

The construction of the screener is best illustrated in Figs. 4, 5 and 6. The screener 40 includes principally a funnel-like casing 50, preferably having the shape of an isosceles trapezoid in horizontal cross-section, and terminating at the bottom in an outlet pipe 51 for feeding material into an observation funnel 52 on the top end of an injector feed pipe 53 having a control valve 54. Projecting upwardly from the top edges 56 of the sloping sides 57 of casing 50 are vertical sides 59 converging in a direction away from the roaster shell, and forming a passage 60 through which oversized material is discharged, over a lip 61, into a collecting pipe 62. Set into casing 50 is a transverse baffle 63 attached at the side edges to sides 57 of casing 50. The baffle slopes downwardly toward the burner shell as shown in section in Fig. 4 and in plan in Fig. 5.

It is to be observed the lower edge 64 of baffle 63 crosses the axis of outlet pipe 51 so that the passage 66 between edge 64 and the back 67 of casing 50 is appreciably more restricted than the passage 70 between the lower edge of baffle 63 and the inner face of front 71 of the casing 50. Baffle 63 forms with back 67 what may be considered a primary hopper 73, and forms with front 71 an overflow hopper 74. The inner top edge of casing 50 may be made arcuate as at 72 to permit the hopper to fit snugly against shell 13.

A screen 71 covers hoppers 73 and 74, and is supported in the position shown in Fig. 4 by rear edge 72, the top edge of the baffle 63, front lip 61 of casing 50, and by the sloping sides 57 thereof.

Referring again particularly to Figs. 1 and 2, the injectors for introducing fines into the furnace comprise a principally metallic pipe section 80, the inner end of which is set into the shell of the burner at the lower end of the combustion chamber, pipe 80 providing an ore inlet 81. Tube 80 is held securely in position by a circular plate 82 and a flange 83 bolted to steel shell 13. In the preferred construction, the axis of tube 80 is directed upwardly at a relatively sharp angle, for example about 75° to the horizontal.

As shown in Fig. 2, the valve-controlled pipe 65 53 projects into the upper side of tube 80. A gas inlet pipe or jet 85 passes through end plate 86 and terminates beneath the discharge end of pipe 53. Admission of air or other gas to jet 85 is controlled by a valve 87. A plug 89 affords 70 means for cleaning out conduit 81 should the same become stopped up.

Surrounding the burner near the injectors is a bustle 90 for supplying gas to injector jets 85, the bustle being connected to a gas supply through 75

a pipe 91 controlled by valve 92. Oxidizing gas to support the roasting operation is introduced into the shell 12 through circumferentially spaced ports 93, positioned adjacent the ore injectors, 5 and connected through short pipe sections not shown with a bustle 94. The bustle 94 may be provided with an inlet pipe connection, having a control valve, either open to the atmosphere or connected to a blower when it is desired to 10 operate the burner under positive pressure.

The bottom of the combustion chamber is formed by a hopper-shaped hearth 95 pitched at an angle preferably slightly less than the angle of repose of the oxide cinder, and terminating 15 in an outlet 96 through which cinder is continuously discharged into a conveyor. A gas main 97 for withdrawing gaseous products of combustion from the chamber 12 opens into the latter just beneath the crown 15.

20 In the specific embodiment of the invention described, the height of the combustion chamber of the furnace, exclusive of the hopper-shaped bottom, is about equal to the diameter. While such particular proportion of the combustion chamber is preferred when carrying out the roasting operation per se in a burner of the general type illustrated in the drawings, it is to be understood that the diameter of the chamber may in some instances advantageously exceed the 25 height by a substantial amount, and may also be less than the vertical dimension. Preferably the diameter of the chamber is not less than the height. It will be understood, however, that the apparatus relative to the means for drying or 30 drying and preheating the fines, prior to introduction into the combustion chamber and relative to the improved screening device may be employed in connection with any kind of roasting chamber.

40 Fig. 3 represents a different type of burner in connection with which the screener 40 may be used to advantage. In this apparatus, the general construction thereof is substantially the same as already described in connection with Figs. 1 45 and 2. However, in Fig. 3, the ore injectors 100 are positioned a relatively short distance beneath the crown 15 so that the finely divided ore is fed into the top of the combustion chamber 12. Screener 40 feeds ore from supply passages 101 50 through inlet pipes 102 into the injectors 100. When employing this type of apparatus, it is preferable to position injectors 100 relatively close to the underside of crown 15, and hence desirable to shorten the distance between the 55 injectors and the screeners as much as possible to conserve head room. Accordingly, angle A (Fig. 4), representing the angle between the surface of screen 17 and the horizontal may be less than would otherwise be the case. In this situation, it may be advantageous to intermittently agitate or shake screener 40 in order to work coarse material over the surface of the screen, and through discharge opening 60. For this purpose, there may be provided a knocker 105 60 rotatably journaled in a bearing 106 carried in the top end of the shell 11. The knocker 105 includes an arm 107 the lower end of which projects into the path of rabble arms 19, and a second arm 108 normally resting against one side 65 70 of screener 40.

Figs. 8 and 9 show a modified construction in which the screen is vibrated electrically. Screen 125, having outwardly projecting sides 126, is pivoted at the rear edge at 127 to the back 67 of 75 casing 50, the opposite edge of the screen ex-

tending over lip 61. Supported by the upper edges of sides 128 of the casing is a bracket 130 carrying a vibrator 131 the casing 132 of which may be rigidly connected to support 130 as at 133. In the center of the bracket 130 is a circular opening 135 through which passes a screen 136 vibrating and supporting rod 137. Attached to the upper end of rod 136 is a vibrator disk 138 spaced from fixed core 139 of the vibrator. Underneath the disk 137 is a nut 140 attached to 1 rod 136 and arranged to bear on the upper side of bracket 130 when the core 139 is demagnetized. The lower end of rod 136 is connected to screen 125 by set nuts 141 which are adjusted so that the outer end of the screen is held spaced 15 slightly above the upper surface of lip 61 of the casing. When the core 139 of the vibrator is demagnetized, the weight of screen 125 and the material thereon is carried by bracket 130 through nut 135 and vibrator rod 136. The upper end of core 139 is threaded into the top of the casing 132 and is provided with a lock-nut 144 by means of which the air gap between disc 137 and the lower end of core 139 may be adjusted. Alternating current is connected to coil 145 by wires not shown.

The invention is applicable to the roasting of metallic sulfide fines such as iron pyrites, pyrrhotite, zinc sulfide or arsenopyrite, but for convenience, and by way of illustration only, the operation of the apparatus may be described in connection with the roasting of iron pyrites.

A supply of relatively finely divided pyrites is maintained in the bin 24 by suitable conveyor or elevator mechanism, not shown. Before 30 roasting is begun, combustion chamber 12 is preheated to temperatures above the ignition point of the particular ore to be roasted, as by the use of oil burners inserted through conveniently located workholes, not shown. When the desired degree of preheat is obtained in the combustion chamber, the motor 22 is started, and rabble arms 19 and sweep 27 may be rotated at a rate of say one revolution in two minutes. Fines run continuously out of the bin 24 onto 45 platform 25, and, on each revolution of shaft 23, a regulated quantity of ore is swept off the platform to approximately the center of hearth 17.

During rotation of rabble arms 19, the fines are gradually worked across the heated surface 50 of hearth 17 into passages 34. The dry or partly dry ore then runs into the louver 35 and the top of jacket 32. The louvers 30 are spaced sufficiently close so that material, while running from one louver into the one immediately below 55 does not overflow the upper horizontal edge of the lower louver, that is, the surface of material between the lower edge of a louver and the upper edge of a subjacent louver, for example, as indicated at 115, is substantially at the angle of 60 repose. The numerous exposed surfaces of the fines between the several louvers permit intermittent exposure to the atmosphere of at least some of the fines and thereby provides for the ready escape of water vapor formed during 65 drying or drying and preheating of the fines.

When roasting is under way, hearth 17, and the vertical walls of the combustion chamber become relatively highly heated, and sulfide fines are dried and preheated to some extent during 70 movement over the drying hearth 17 and through jacket 32 surrounding preferably at least a major portion of the burner shell. This operation blankets the top and sides of the burner with ore which acts as a heat insulator, retaining heat 75

in the combustion chamber, and employing heat which is transmitted through shell 11, to the ore, to dry and heat the latter. This preliminary heating serves to dry the fines, thus facilitating the formation of more satisfactory dispersion of ore in the combustion chamber, and at the same time preheats the fines to temperatures, say 300 to 400° F., so as to promote ignition shortly after introduction into the combustion chamber.

5 The fines dried, or dried and preheated, on passage thru jacket 32 are directed by sloping edges 45 toward outlets 38 through which the material is fed to the subjacent screeners 40, before injection into the combustion chamber. The operation of the screening devices may be understood from a consideration of the enlarged section shown in Fig. 4.

10

15

20 Fines are continuously fed into passage 101 by plows 20 of rabble arms 19. In normal operation, passages 101 are maintained filled with material, and the pitch of passages 101 is such as to tend to continuously feed fines onto screen 17. The slope of the latter, represented by angle A, is preferably such that oversize material 25 is gradually worked over the surface of the screen and discharged through opening 60. Generally speaking, the upper horizontal edge 116 of baffle 63 is spaced with respect to the burner shell 13 so that the remote edge or toe 117 of the mound 30 118 of material on top of the screen 77 lies about at the position of horizontal edge 116 of the baffle 63, and so that the upper surface of the mound 118 assumes the angle of repose. According to the nature and particular size of the 35 particular fines, the position of the toe 117 may be adjusted by vertically slidable gate 120 so that toe 117 lies substantially above the upper edge of the baffle 63. By this arrangement, there is maintained on the screen above hopper 73 a given amount of material which acts in turn to 40 lute off passage 101 and control the amount of ore fed therefrom to the screen.

The bulk of the material passes through screen 17 and into the primary hopper 13 from which the fines are withdrawn through passage 66, and pipe 51 into observation funnel 52 on the top of feed pipe 53. From a consideration of Fig. 4, it will be seen that if material less than screen size works down over the surface of the screen and passes the upper edge of baffle 63, such undersized material will pass through the lower end of the screen and into the overflow hopper 14. This construction prevents discharge over lip 61 of material of less than screen size. It will be observed lower edge 64 of baffle 63 crosses the axis of outlet pipe 51 so that the passage 70 is larger than passage 66. For this reason, screened material will feed out of hopper 14 into pipe 51 at a rate faster than out of hopper 13. Accordingly, material collecting in hopper 14 is quickly fed out through opening 70 into the funnel 52 thus insuring an empty or at least partially empty overflow hopper 14.

65 As valve 54 is opened and adjusted to regulate the rate of withdrawal of fines from hopper 13, a corresponding amount of ore flows out of passage 101 onto the upper surface of screen 77.

Where, as in Fig. 4, the angle A is not quite sharp enough to effect prompt discharge of oversized material, such discharge may be had by movement or agitation brought about by knocker 105 which, on each contact with a rabble arm 19, is raised and dropped against the casing 50 to agitate the same and help work oversized ma-

terial off screen 77 and out through opening 60.

In the operation of the screener 40, only the equivalent of the ore withdrawn through pipe 53 can be fed to screen 77. As the same amount of material is fed to the screen as is withdrawn continuously through pipe 53, segregation of relatively fine and coarse undersize material is prevented. The feed conduits to the screen, such as passages 101, are sealed by material on the screen, and overflow of the screen is avoided. Coarse oversize material is discharged without blocking the hopper, and material of less than screen size which might be discharged along with the oversize material is caught in overflow hopper 74, and directed into the ore injector through pipe 53.

The operation of the screener of Fig. 1 is substantially the same as described in connection with Fig. 4. In Fig. 1, it will be understood the construction is so that the horizontal spacing between the upper edge of baffle 63 and the lower edge of bottom louver 43 is such that a line drawn between the two represents with the horizontal approximately the angle of repose of the particular material being used for roasting. If desired, a small adjustable gate corresponding with gate 120 of Fig. 4 may be attached to the lower edge of louver 42 so as to permit horizontal adjustment of the position of the toe of fines on the surface of screen 17 relative to the upper edge 116 of baffle 63.

In the operation of the modified apparatus shown in Figs. 8 and 9, a mound of material 118 is maintained on screen 125 as already described in connection with Fig. 4. In the construction of Figs. 8 and 9, however, provision is made for continuously vibrating screen 125. When coil 145 of vibrator 131 is connected to a source of alternating current, it will be understood core 138 is alternately magnetized and demagnetized and disc 137 carrying screen 125 is raised to engage the lower end of core 138, and then drops back to the position shown in Fig. 8. It will be understood this construction continuously vibrates screen 125 about pivot 127 thus insuring continuous feed to the hoppers 73 and 74, and avoiding clogging of the screen. This construction may be employed to advantage where the angle formed by the surface of screen 125 and the horizontal is not sharp enough to effect prompt discharge of oversized material from the screen.

Valves 54 in feed pipes 53 are adjusted so that a substantially steady stream of fines runs into feed conduits 81. The fines are then injected into the combustion chamber 12 by means of air, steam, or other gas not adversely affecting oxidation of the sulfide. It is preferred to employ air for this purpose, and when using the latter, air may be introduced into the lower ends of conduits 81 through valve-controlled jets 85 at pressures of about 5 pounds per square inch. When starting up roasting operations, it will be understood the combustion chamber 12 is preheated to above ignition temperature of the fines by oil burners or other convenient means not shown. 65

The axes of inlet conduits 81, Fig. 1, the amount of fines fed into the injectors through pipes 53, and the air pressure in jets 85, regulated by valves 87, are all adjusted with respect to the particular size of the roasting chamber so that 70 the ore particles from each injector rise through the combustion chamber to an elevation just below the undersign of crown 15. Ore particles then fall to hearth 95, and while passing through an atmosphere increasingly rich in oxygen oxy- 75

dation of the fines is completed. It will be understood in the embodiment of the invention shown in Fig. 1, the major portion of the air for roasting is drawn into the combustion chamber 5 through ports 93 by a suction fan in the gas outlet conduit 97 through which the gaseous products of roasting are withdrawn. The roasting operation per se is no part of the present invention, and hence need not be further detailed.

10 The operation of the apparatus of the invention when used in connection with the burner illustrated in Fig. 3 is thought to be apparent from the description already given relative to the enlarged section shown in Fig. 4. However, when 15 employing the apparatus of Fig. 3, it will be understood the fines are injected into the upper end of the combustion chamber and fall through a rising current of air or other oxidizing gas introduced into the bottom of the combustion zone 20 as in the apparatus of Fig. 1.

The sulfur dioxide gases produced may be used, for example, in the manufacture of sulfuric acid. The sulfur dioxide content of the burner gas may be regulated as desired by adjusting the amount 25 of air fed into the combustion chamber as is known by those skilled in the art. Gases containing 10-13% sulfur dioxide may be readily made by the present process.

We claim:

30 1. Apparatus for screening material comprising a casing, a sloping screen covering the casing, an outlet at the bottom of the casing, a baffle in the casing forming primary and overflow hoppers, the upper edge of the baffle lying against the screen 35 and the lower edge of the baffle being positioned, with reference to the axis of the casing outlet, toward the material feed end of the screen, means for feeding material to the higher end of the screen, means for discharging oversized material over the lower end of the screen, and means for 40 withdrawing material from the bottom of the casing.

2. Apparatus for screening material comprising a casing, a sloping screen covering the casing, an outlet at the bottom of the casing, a baffle in the 45 casing forming primary and overflow hoppers, the baffle sloping downwardly in a direction toward the high end of the screen, the upper edge of the baffle lying against the screen and the lower edge of the baffle being positioned, with 50 reference to the axis of the outlet conduit, toward the material feed end of the screen, means for feeding material to the higher end of the screen so as to maintain the toe of the mound of material thereon adjacent the edge of the baffle, means for 55 discharging oversized material over the lower end of the screen, and means for withdrawing material from the bottom of the casing.

3. Apparatus for screening material comprising a screen, a casing provided with a discharge 60 opening beneath the screen, a baffle in the casing forming with the walls of the casing a primary hopper and an overflow hopper, each of said

hoppers having discharge openings formed by the lower edge of the baffle and the walls of the casing communicating with the discharge opening of the casing, the discharge opening of the overflow hopper being larger than the discharge 5 opening of the primary hopper, means for feeding material to the screen above the primary hopper, means for discharging oversize material from the end of the screen beyond the overflow hopper and means for withdrawing material from the discharge opening of the casing. 10

4. Apparatus for screening material comprising a casing having side walls, the said walls having upper edges forming an angle with the horizontal, a screen disposed above the casing at the same 15 angle as the upper edges of the side walls of the casing, a baffle in the casing dividing the casing into a primary hopper having as side walls the higher portions of the side walls of the casing and an overflow hopper having as side walls the 20 lower portion of the side walls of the casing, means for introducing material to be screened onto the screen above the primary hopper, and means for withdrawing oversized material from the screen beyond the overflow hopper, the angle 25 of the upper edges of the side walls of the casing and the screen being such as to maintain a mound of the material on the screen so that the toe of the mound is adjacent the upper edge of the baffle and the upper surface of the mound of 30 material is substantially at the angle of repose of the material.

5. Apparatus for screening material comprising a casing, a screen covering the casing, an outlet at the bottom of the casing for withdrawing 35 material therefrom, a baffle in the casing forming primary and overflow hoppers, the upper edge of the baffle lying against the screen and the lower edge of the baffle being positioned, with reference to the axis of the casing outlet, toward 40 the outer end of that portion of the screen covering the primary hopper, means for feeding material to said outer end of the screen, and means for discharging oversized material over the opposite end of the screen. 45

6. Apparatus for screening material comprising a casing, a screen covering the casing, an outlet at the bottom of the casing, for withdrawing material therefrom, a baffle in the casing forming primary and overflow hoppers, the upper edge of 50 the baffle lying against the screen and the lower edge of the baffle being positioned, with reference to the axis of the casing outlet, toward the outer end of that portion of the screen covering the primary hopper, means for feeding material to 55 said screen so as to maintain the toe of the resulting mound of material on the screen covering the primary hopper not substantially beyond the edge of the baffle, and means for discharging oversized material over the opposite end of the screen. 60
